UNITED STATES PATENT OFFICE.

JAMES B. SMALLEY AND CHARLES A. REINERS, OF CHICAGO, ILLINOIS,
ASSIGNORS TO THE ELEVATOR SUPPLY AND REPAIR COMPANY, OF
SAME PLACE.

ELECTRIC SIGNALING APPARATUS FOR ELEVATORS.

SPECIFICATION forming part of Letters Patent No. 634,220, dated October 3, 1899.

Application filed September 22, 1898. Serial No. 691,652. (No model.)

To all whom it may concern:

Be it known that we, JAMES B. SMALLEY and CHARLES A. REINERS, residents of Chicago, Cook county, Illinois, have invented certain new and useful Improvements in Electric Signaling Apparatus for Elevators, of which we do declare the following to be a full, clear, and exact description.

The present invention has relation more particularly to that class of elevator-signaling apparatus in which an electric signal-lamp is carried by each of the elevator-cars and in which signal-lanterns are arranged upon various floors of the building through which the elevators travel, push-button mechanism being provided adjacent the doorways of the elevator-shaft in order to enable the intending passenger to cause the signal-lamps within the car to burn and to cause the lamps within the signal-lanterns to burn as the car approaches the floor at which the push-button mechanism has been operated. An example of this general type of electric signaling apparatus is set forth in Letters Patent No. 499,411, granted to Armstrong and Adler June 13, 1893.

The present invention consists in features of improvement hereinafter described, illustrated in the accompanying drawings, and particularly pointed out in the claims at the end of this specification.

Figure 1 is a diagrammatic view showing our invention as applied to two adjoining passenger-elevators. Fig. 2 is a detail plan view of the master-commutator. Fig. 3 is an inverted plan view of the master-commutator. Fig. 4 is a view in vertical cross-section through the commutator, the section being taken at one side of the brush-supporting arm. Fig. 5 is a plan view of one of the supplemental commutators. Fig. 6 is a view in vertical cross-section through the supplemental commutator shown in Fig. 5, the section being taken through the brush-supporting arm. Fig. 7 is a detail view, in longitudinal section, through the brush-supporting arm beneath the commutator. Fig. 8 is a detail view, partly in elevation and partly in section, showing the means for driving the com-

mutator-shaft and the overhead shaft of the 50 elevator.

Referring to Fig. 1 of the drawings, A and A' denote, respectively, two elevator-cars that will be arranged within suitable shafts, so that they will pass in usual manner through the several floors of the building, the floors being designated in conventional manner in Fig. 1. Within each of the cars A and A' is placed a signal-lamp B, and within each of the cars is also placed a transferring-button 60 C, the purpose of which is to enable the operator within a car to transfer the signal to the next car in case his car is so actuated as to prevent its taking on a passenger who has signaled the elevator, as will herein more 65 fully appear. At each floor of the building is provided a push-button box D, by which the passenger is enabled to close a normally open electric circuit and by so doing to set the mechanism whereby as the car approaches his floor 70 the signal-lamp within the car will be caused to burn and whereby the corresponding signal-lantern upon such floor will also be caused to burn. Upon the top floor the push-button box D contains but a single push-button or circuit- 75 closer, and the same is true also of the push-button box D upon the bottom floor; but the push-button box on the intermediate floors are provided each with two push-buttons, one serving to give the "up" signal and the other serving to give the "down" signal. So, also, upon the top floor of each elevator-shaft is placed a single signal-lantern E, and in like manner at the bottom floor is placed a single signal-lantern F, while two signal- 85 lanterns E and F are provided adjacent the doorway of each elevator-shaft upon each elevator-floor between the top and bottom of the building. The apparatus illustrated in the accompanying drawings is shown as applied to two adjacent elevators; but it will be manifest that without material change the system may be extended to any number of elevators. Where two elevators are employed in proximity to each other, a single set of 90 push-button boxes will suffice for both. 95

When the passenger upon any floor desires to signal an elevator-car, he will push one or

the other of the buttons in the corresponding push-button box, the upper button being depressed if he desires to go upward or the lower button if he desires to descend. By 5 thus pushing one or the other of the buttons the intending passenger brings into operation the commutator mechanism next to be described and which for convenience is usually located at the top of the elevator-shafts, although it might be located in any other convenient position.

The sustaining-frame of the commutator mechanism is shown as comprising side bars G and G', that are united by the bottom plate G² and by the cross-bars g, g', g², g³, g⁴, and g⁵. Upon the side bars G and G' and within suitable bearings h is journaled the commutator-shaft II, the part of this shaft between the side bars of the sustaining-frame being 20 formed as a screw. The shaft II will be driven from the overhead shaft of one of the elevators, and preferably a friction mechanism will be interposed at a point between said overhead shaft and the shaft II, for a purpose 25 to be presently stated. One suitable form of mechanism whereby motion will be transmitted to the shaft II is illustrated in Letters Patent No. 511,987, granted to Fred Andrews January 22, 1894, or preferably the outer 30 portion of the elevator-shaft II will have loosely mounted thereon a sprocket-wheel II', at opposite sides of which are placed friction-disks h' and h², the friction-disk h' being interposed between an annular shoulder of the 35 shaft H and the sprocket-wheel, while the friction-disk h² is interposed between the sprocket-wheel and a collar h³. As shown, the collar h³ is formed with grooves to receive pins h⁴, projecting from the shaft, and 40 against the collar h³ bears a coil-spring II², the tension of which is controlled by suitable set-nuts h⁴ upon the threaded outer end of the shaft. It will thus be seen that the sprocket-wheel II' is held upon the shaft by 45 frictional engagement with the collar and the shoulder at opposite sides thereof, so that when the parts carried by the screw-threaded body of the shaft reach the end of their travel any further revolution of the shaft will not 50 endanger the breakage of the parts, and any tendency of the elevator-cable to "creep" will not influence the movements of the parts carried by the threaded body of the shaft II.

Upon the threaded portion of the shaft II is mounted an interiorly-threaded carrier-nut II³, that is provided at its opposite ends with the shoulders h⁵, and upon the shaft II, adjacent the ends of its body-thread, are fixed the nuts II⁴ and II⁵. As shown, the nut II³ 55 serves to sustain a cross-arm I, and for this purpose the carrier-nut is shown as provided with a raised standard h⁶, (see Figs. 4 and 6,) to which the cross-arm I is attached by screws h⁷. A suitable insulating-plate is interposed 60 between the top of the standard h⁶ and the cross-arm I, and suitable insulating-sleeves h⁸ encircle the screws h⁷ where they pass

through the cross-arm I. The standard h⁶ is shown as hollow, and within the standard is set a friction-block h⁹, that will fit between 70 the screw-threads of the shaft II and bear frictionally upon the shaft. In order to give the proper frictional bearing upon block h⁹, a coil-spring h¹⁰ is set within the standard h⁶, and upon this coil-spring bears a plate that 75 is carried by the lower end of an adjusting-screw h¹², that passes through a correspondingly-threaded hole in the cross-arm I, the position of the screw with respect to the cross-arm being determined by a set-nut h¹³. 80

One end of the cross-arm I serves to carry the contact points or brushes K, K', and K², while the other end of the cross-arm I carries the contact-brushes K³, K⁴, and K⁵. The brushes K and K³ are shown as consisting of 85 screws passing through flanged sleeves, of insulating material, held within corresponding openings at the ends of the cross-arm I, the position of the screws K and K³ being determined by suitable set-nuts. The contact points or brushes K', K², K⁴, and K⁵ are shown at the ends of rods h¹, h², h⁴, and h⁵, that pass, respectively, through the hollow stems h⁶, h⁷, h⁸, and h⁹. The stems h⁶, &c., have coiled 95 springs h¹⁰ therein that serve to force downwardly the contact-points beneath them, and the stems h¹ and h⁴ have their upper ends screw-threaded to receive nuts h¹², that limit the downward movement of the stems. The sleeves h⁶, &c., are insulated from the cross-arm I by means of flanged sleeves or collars, of insulating material, as clearly shown in Fig. 6 of the drawings. From the carrier-nut II³ extends an arm II⁶, preferably cast integral with the nut, and at opposite sides of 100 the arm II⁶ extend the supplemental cross-arms II⁷ and II⁸. (See Fig. 3.) The supplemental cross-arms II⁷ and II⁸ are fastened to a short shaft II⁹, that passes loosely through an opening formed in the lower part of the 105 depending arm II⁶. The supplemental cross-arm II⁷ has holes formed in its opposite ends, within which are set sleeves, of insulating material, by which are carried the contact points or brushes i and i'. (See Fig. 7.) The contact point or brush i is shown as consisting of a single screw held in place by threaded nuts, while the contact-brush i' is shown as mounted within a hollow stem i², that carries a coil-spring i³, forcing the brush normally 110 upward. The lower end of the stem i² is provided with a set-screw i⁴, to which will be attached an electric wire, as will hereinafter appear. In like manner also the ends of the supplemental cross-arm II⁸ are provided 115 with openings, in which are set sleeves, of insulating material, by which are carried the contact points or brushes j and j', that correspond in construction and arrangement with the contact points or brushes i and i', as last described. 120

Upon the cross-bars g' and g² is mounted a plate M, (the plate being shown as of double thickness,) of insulating material, and upon the cross-bars g³ and g⁴ a similar plate M' of 125

insulating material is fixed. On the plate M is mounted a bar of insulating material m, provided at intervals along its length with metal contact-plates 2, 3, 4, 5, and 6. Adjacent the rail m is a similar rail m', provided at intervals with metallic contact-plates 7 8 9 10 11, and adjacent the rail m' is a contact-bar m². In like manner upon the opposite side of the screw-shaft H is a contact-bar m³, corresponding to the bar m², a rail m⁴, provided with contact-plates 12, 13, 14, 15, and 16, and a rail m⁵, provided with contact-plates 17, 18, 19, 20, and 21. The rails m and m' and the contact-bars m² extend, respectively, beneath the path of travel of the brushes K³, K⁴, and K⁵, while the contact-bar m³ and the rails m⁴ and m⁵ extend, respectively, beneath the travel of the brushes K², K', and K. The carrier-nut H³ is so mounted on the screw-shaft H that as the shaft is revolved in one direction the brushes at one end of the cross-arm I will bear against the contact-bar and rails beneath them, and preferably one of the contact-brushes at the opposite side of the screw-shaft will bear upon its subjacent contact-bar; but when the direction of travel of the screw-shaft H is reversed the contact-brushes at the opposite end of the cross-arm I will be moved into operative position, while the brushes that were before in operation (except the brush that rides upon the contact-bar) will be raised to an inoperative position. The purpose is to have the two outer contact-brushes at one end of the cross-arm I in action as the carrier-nut H³ moves in one direction, the corresponding contact-brushes at the opposite end of the shaft being at such time out of action, and when the direction of travel of the carrier-nut H³ is reversed the two outer brushes that were before in action will be thrown out of action, while the opposite brushes will be brought to operative position. The movement of the carrier-nut H³ in one direction corresponds with the upward movement of the elevator-car, while the movement of the carrier-nut H³ in the opposite direction corresponds with the downward movement of the elevator-car, it being understood that the friction-gear mechanism whereby the shaft H is driven from the overhead shaft of the elevator is a reducing-gear, so that but a very short travel of the carrier-nut H³ will occur even where elevators are moving through floors of tall buildings. When the carrier-nut H³ reaches the end of its travel in one direction, its shoulders h⁵ will contact with corresponding shoulders on the fixed nut or sleeve H⁴, and when the carrier-nut H³ is moving in opposite direction the shoulders h⁵ at its opposite end will in like manner contact with corresponding shoulders formed upon the end of the fixed nut H⁵, so that the nuts H⁴ and H⁵ serve to arrest the movement of the carrier-nut H³ in both directions. Hence it will be seen that if there is any tendency of the elevator (by reason of the creeping of its cable or other cause) to move the carrier-nut H³ farther than the fixed nuts H⁴ and H⁵ the sprocket-wheel II' will turn upon the shaft H, the frictional engagement of the sprocket-wheel on the shaft being merely adequate to drive the shaft H. The nuts H⁴ and H⁵ are adjustable upon the threaded portion of the shaft H, so that the carrier-nut H³ can be arrested at any desired point adjacent the end of the movement of the elevator-car.

In order to insure the tilting of the cross-arm I and of the carrier-nut H³, whereby this arm is carried, for the purpose of alternately bringing the brushes at the respective ends of the cross-arm I into and out of operative position and as well also to relieve the arm and the contact-brushes from all strain when the movement of the carrier-nut H³ is arrested, it is preferred to employ the means next to be described, viz: Through each of the side bars G and G' of the commutator-frame extend inwardly screw-bolts N and N', the unthreaded inner ends of which pass through the bosses o of the bracket O. From the bosses o of the bracket O extend upwardly the arms o' and o², the arm o' being formed at its top with a bearing-head o³, while the arm o² is formed at its top with a bearing-head o⁴. The bearing-head o³ has the under side of its inner end beveled, (see Figs. 2 and 4,) while the bearing-head o⁴ has the upper face of its inner end beveled. From one side of the carrier-nut H³ project the flanges o⁵ and o⁶, and from the opposite side of the carrier-nut project similar flanges o⁷ and o⁸. The bearing-heads o³ and o⁴ are arranged in different horizontal planes, (the purpose of which will hereinafter appear,) and these bearing-heads serve to engage the laterally-projecting flanges o⁵, o⁶, o⁷, and o⁸ in order to insure the shifting of the carrier-nut H³ and of the cross-arm I and as well also to relieve the cross-arm from strain in event of any tendency of the shaft H to revolve after the carrier-nut has been arrested by either of the fixed nuts H⁴ or H⁵ at the end of its travel. Thus, for example, if the carrier-nut H³ be assumed as moving in the direction of the arrow, Fig. 2, then as the carrier-nut reaches the end of its travel the flange o⁷ at the side of the carrier-nut will ride up the inclined end and onto the top of the bearing-head o⁴, while at the same time the flange o⁶ at the opposite side of the carrier-nut H³ will contact with the lower inclined surface at the end of the bearing-head o³. Hence as the carrier-nut completes its travel in the direction of the arrow, Fig. 2, the carrier-nut H³ and the cross-arm I will be oscillated, so as to cause the cross-arm to tilt to a position opposite to that shown in Fig. 4 of the drawings and in so doing to throw the contact points or brushes K and K' into operative position and the contact-points K³ and K⁴ out of operative position. It will also be seen that if after the carrier-nut H³ has thus reached the end of its travel there is any tendency for the shaft H to further revolve the flanges o⁶ and o⁷, bear-

ing, respectively, against the heads o^4 and o^5 , will take the strain incident to such further revolution of the shaft II and cause the slipping of the sprocket-wheel H' upon the outer end of the shaft II, thus preventing this strain from being thrown upon the contact-brushes at the ends of the cross-arm I. Upon the bottom plate G² of the commutator-frame is also mounted a guard-bar G⁶, that extends (see dotted lines, Fig. 5) throughout a portion of the path of travel of the carrier-nut II³, and this bar G⁶ rises somewhat higher than the lower end of the depending arm II⁶. Hence it will be seen that as the carrier-nut II³ and the arm II⁶ move in one direction the lower end of the arm II⁶ will travel along one side of the guard-bar G⁶, while as the carrier-nut II³ and the arm II⁶ move in the opposite direction the lower end of the arm will move along the opposite side of the guard-bar G⁶. If, therefore, there is any reversal of the direction of travel of the elevator-car at points between the extremes of its movement—as, for example, when a floor has been accidentally passed and is returned to by the car—the guard-arm will serve to prevent any reverse oscillation of the carrier-nut and the cross-arm I, sustained thereby, and hence the guard-bar G⁶ will insure the proper travel of the contact-brushes at each end of the cross-arm I throughout the entire movement of the cross-arm as the elevator-car is moving in upward or downward direction. As the elevator-car, however, completes its movement in upward or downward direction the depending arm II⁶ passes beyond the ends of the guard-arm G⁶, and hence the oscillation of the carrier-nut II³ and the cross-arm I can be effected, as hereinbefore described. By reference to Figs. 4 and 6 of the drawings it will be seen that as the depending arm II⁶ of the carrier-nut is oscillated at the end of its travel in either direction a lateral shift will be given to the cross-arms H⁷ and H⁸ and to the contact points or brushes carried by these arms. The contact-points i' and j' are adapted to travel along contact-plates 25 26 27 28 29 30 and contact-plates 31 32 33 34 35 36, that are mounted upon a plate 37, of insulating material, carried at the lower ends of the posts 38, and the contact points or brushes i' and j' are adapted to ride against the contact-plates 40 41 42 43 44 45 and 46, 47, 48, 49, 50, and 51, that are fixed to the under side of the plate 52, of insulating material, this plate 52 being attached to the depending posts 53. The contact-plates that are engaged by the various brushes or contact-points carried by the cross-arm I and by the supplemental cross-arms H⁷ and H⁸ are arranged in correspondence with the floors of the building through which the elevator-car passes, the contact-plates at one side of the screw-shaft II being designed for operation as the car is moving in upward direction, while the contact-plates at the opposite side of the shaft are designed to operate when the car is mov-

ing in downward direction. Inasmuch as there will be no "up" signal transmitted from the top floor of the building and no "down" signal transmitted from the bottom floor, it is manifest that the number of contact-plates opposite the path of travel of each contact brush or point will be one less than the total number of floors in the building.

Upon the frame of the "master-commutator," as it is conveniently termed, (this being the commutator shown in Figs. 2, 3, and 4 of the drawings,) it is deemed preferable to place the mechanism next to be described, although it will be readily understood that such mechanism could be placed at any convenient point more or less remote from the commutator. As shown, cross-bars G⁷ and G⁸ extend between the side bars G and G' of the commutator-frame at each side of the mechanism hereinbefore described. Upon each of the cross-bars G⁷ and G⁸ is mounted a series of electromagnets R R' R² R³ R⁴, suitable insulating-strips g⁷ being interposed between the bars G⁷ and the magnets. Adjacent each of the magnets R R', &c., rises a standard r, in the upper bifurcated end of which is pivotally sustained the armature r' of a corresponding magnet. Each armature r' is shown as provided with a set-screw r², adapted to contact with the stop r³, projecting from the bracket r. Through the end of each armature r' passes a contact-rod s, preferably having a reverted threaded end, with which engage set-nuts s' and s², by which the position of the contact-rod s can be accurately determined. Opposite the magnets R R', &c., are placed the mercury-pots S, S', S², S³, and S⁴, that rest upon the insulating-plate M, that extends across the top of the commutator-frame. The magnets R R', &c., are the "restoring-magnets," and their function and mode of operation will presently appear.

Adjacent the magnets R R', &c., and preferably arranged as shown, are the releasing-magnets T, T', T², T³, and T⁴, these magnets being suitably attached to the cross-bar G⁸ of the commutator-frame. A bracket t extends adjacent each of the magnets T T', &c., and to the end of the bracket is pivoted the armature t' of the corresponding magnet. Each armature is shown as provided with an angular end having a threaded opening to admit a set-screw t², that will engage with the bracket t and will thus determine the extent of movement of the armature t'. The cross-bar G⁸ has vertical slots formed in its ends, and through these slots pass the clamping-bolts g⁹, that pass through holes formed in the upturned end of the side bars G and G' of the main frame. (See Fig. 2.) By this means the plate G⁸ can be raised or lowered in order to adjust the series of magnets G G', &c., and their armatures with respect to the armatures of the magnets R R', &c. Upon the cross-bar G⁸ is carried a plate G¹⁰, of insulating material, whereon are mounted a series of binding-posts U.

Referring more particularly to Fig. 4 of the drawings, it will be seen that the armature t' of each of the magnets T is arranged in such position that it will engage with the 5 end of the armature r' of the corresponding magnet R, and when in such position it will hold the armature r' elevated, as shown in Fig. 4, and will thus hold the contact-rod s out of the mercury within the corresponding 10 pot S. When, however, current is caused to pass through one of the magnets T, thereby energizing the same, the armature t' will be attracted and will pass from engagement with the end of the armature r' , thereby releasing 15 the armature r' and permitting the contact-rod s to dip into the mercury-pot and establish current through such pot, as will presently appear.

When an intending passenger operates the 20 push-button mechanism upon either floor of the building, the first result is to close the normally open circuit in which the push-button mechanism and the corresponding releasing-magnet are placed. Inasmuch as this 25 circuit requires but slight current, it is preferred to supply such current from a rotary transformer or battery, a rotary transformer V being shown in the drawings for this purpose. Referring to the diagrammatic view, 30 Fig. 1, it will be seen that from the transformer V a wire v extends to a switch W, that is located within the elevator-shaft. The purpose of this switch and of the signal-bell W', that is connected to the switch by 35 the wire w , will hereinafter more fully appear. From the contact-post x of the switch W a feed-wire x' leads adjacent the several push-button boxes D, branches from this feed-wire x' leading to each of the push-but- 40 tons within the boxes. From the push-button box D on the bottom floor a wire x^2 leads to a resistance coil or magnet X, and from this coil a feed-wire x^3 leads to the rotary transformer V. From the feed-wire x^3 branch 45 wires lead to the several releasing-magnets T T', &c., these magnets being arranged in multiple, as shown. It will be observed that the push-button of the top floor is also connected by a branch wire d with the wire x^2 , 50 and a branch wire leads from the opposite side of this push-button to the feed-wire x' .

Inasmuch as the present signaling system is more especially adapted for rapid-service elevators, such as those used in office buildings, it is not deemed necessary to light the 55 signal-lamp in the car either at the top or bottom floors, because when the elevator-car reaches these points it must stop and the car is supposed to run continuously throughout 60 the day. The push-buttons at the top and bottom floors do not, therefore, when operated cause passage of current through any of the releasing-magnets, but simply close the circuit in which the rotary transformer 65 v is interposed. Thus, for example, if the push-button on the bottom floor be operated current will pass as follows, viz: from trans-

former V, by wire v , through switch W (normally closed) to push-button on the first floor, thence by wire x^2 to resistance-magnet X, and 70 thence by feed-wire x^3 back to the transformer V.

At night and on Sundays or holidays it is the custom in large office buildings to put most of the elevators out of service and to 75 permit those that remain in service to rest at either the top or bottom floors. At such time it becomes desirable that an intending passenger on the top or bottom floor should be able to signal or notify the elevator-operator. It is for this reason that the switch and bell W and W' are employed, and at nights, 80 holidays, or the like the switch W will be opened, as seen in Fig. 1, so as to throw the bell W' into circuit. When the switch W is 85 thus opened and the push-button at the top and bottom floors (or indeed at any floor) is depressed, current will pass from the transformer through the signal-bell W', and the operator hearing this bell will know that there 90 is a passenger awaiting service.

The purpose of the resistance-coil of the magnet X, the resistance of which equals that of the several magnets T T', &c., is to prevent the whole body of current passing 95 directly by the shortest circuit in which the rotary transformer of the push-buttons of the top and bottom floors are interposed in event it should happen that a push-button upon any of the intermediate floors should be operated at the same time with the operation of the push-buttons at the top or bottom floors, since, manifestly, if the whole body of current were permitted to pass by the shortest 100 circuit through the push-button at the top or bottom floor back to the rotary transformer V there will be no current to actuate the releasing-magnets T T', &c., if it so happened that a simultaneous operation of the top or 105 bottom floor push-buttons and any intermediate push-button occurred. The function of the resistance coil or magnet X will, however, more fully appear from the following 110 description: Each "up" push-button (except that on the bottom floor) is connected by a 115 wire with a corresponding releasing-magnet on the left-hand side of the screw-shaft H. Thus by reference to Fig. 1 it will be seen that the "up" button on the sixth floor is 120 connected by a wire e with the releasing-magnet T at the left-hand side of the commutator, the "up" push-button on the fifth floor is connected by a wire e' with the releasing-magnet T', the "up" push-button on the fourth floor is connected by a wire e^2 with the releasing-magnet T², the "up" push-button on the 125 third floor is connected by a wire e^3 with the releasing-magnet T³, and the "up" push-button on the second floor is connected by a wire e^4 with the releasing-magnet T⁴. A wire 130 t^5 connects the several magnets T T', &c., with the wire x^3 , that leads to the rotary transformer V. Hence it will be seen that if the "up" push-button upon the sixth floor,

for example, be operated to close the circuit at such point current will pass from the transformer V, by wire v, through switch W and wire x' to such push-button box, and 5 thence by wire e to releasing-magnet T, and thence by wire f⁵ and by wire x³ to the transformer. This passage of current through releasing-magnet T will energize the magnet, causing its armature r to be attracted and to 10 release the armature r' of a corresponding restoring-magnet R, and this release of the armature r' will permit the contact-rod s to dip into the corresponding mercury-pot S, in order to establish passage of current at such point. 15 In like manner also it will be apparent that when any push-button on a floor between the top and bottom is depressed current will be caused to pass through the corresponding releasing-magnet T' T', &c., and the armature 20 of the corresponding restoring-magnet R R', &c., will be released.

By reference to Figs. 1 and 4 of the drawings it will be seen that the signal-lamp B upon the car A is connected by a branch wire 25 b with a feed-wire f, that leads to a dynamo Y, that will be located at the power-house or other remote point, and from such lamp B another wire b' will lead to the contact-plate m², over which plate travels the contact brush 30 or point K⁵. (See Figs. 4 and 6.) The holding-sleeve of the contact-brush k⁵ is connected by wires n and n' to the contact brush or point K³, that travels over the contact-plates 1, 2, 3, 4, 5, and 6, and each of the contact- 35 plates 1 2 3, &c., is connected by a short wire to its corresponding mercury-pot S S', &c. Hence it will be seen that when the "up" push-button on the sixth floor, for example, has been operated, causing the magnet T to 40 be energized and causing the armature r' of the restoring-magnet R to be released, thus permitting the rod s to drop into the mercury-pot S, current will pass from the dynamo Y as follows, viz: by wire f and branch wire b 45 to electric lamp B in car A, thence by wire b' to contact bar or plate m², against which the contact-brush K⁵ travels at all times. Now bearing in mind the fact that the contact-brush K⁵, as well as the other contact-brushes 50 that are moved by the carrier-nut H³, travel in unison with the movement of the elevator-car and the further fact that the contact-brushes K³, K⁴, and K⁵ are operative during the upward movement of the car it will be 55 seen that as the elevator-car moves upward from the bottom floor of the building the contact-brush K³ will pass onto the contact-plate 2 about the time that the elevator-car in its upward movement passes the fifth 60 floor and at such time current that has, as above described, passed from the dynamo Y to the contact plate or bar m² will pass from plate m² to contact-brush K⁵ and its sleeve to wire n, to wire n', to contact-brush 65 K³, to contact-plate 1, thence by a short wire to mercury-pot S, thence by contact-rod s to armature r of magnet R, thence by

bracket r and contact-plate R⁶ to wire f², and thence by wire f³ back to the dynamo Y. The passage of current in manner just described 70 will cause the lamp B within the car A to burn. The contact-plate 2 is so arranged that the contact-brush K³ will pass thereon about the time that the elevator-car in its upward travel moves from the fifth floor of the 75 building, so that the signal-lamp within the car will give ample notice to the operator when a party is awaiting for upward service upon the sixth floor. In like manner also it will be seen that if the "up" push-button on 80 the second floor, for example, is operated the magnet T⁴ will be energized, thereby permitting the contact-rod s to drop into the mercury-pot S⁴ and close the signal-lamp circuit at such point. A car at rest at the first floor 85 will have its signal-lamp at once lighted, for the reason that when the car is at the first floor the carrier-nut H³ has been turned so as to oscillate the cross-arm I in order to bring the contact-brushes K³ and K⁴ into operative 90 position, and the contact-brush K³ will at once bear upon the contact-plate 6. Hence it will be seen that current will pass from the dynamo Y through the lamp B of the car A, and thence by wire b' to the contact-plate m². 95 From this plate current will pass to contact-brush K⁵, thence by wire n to wire n', to contact-brush K³, which at such time will be resting upon contact-plate 6. From contact-plate 6 current will pass by a short wire to mercury-pot S⁴, and thence by contact-rod s, armature r' of magnet R⁴, to bracket r and contact-plate R⁶, to wire f², to dynamo Y. The light B within the car will thus be caused to burn. As soon, however, as the contact-brush K³ 100 passes from off the contact-plate 6 the circuit will be broken at such point and the light within the car will be extinguished.

The magnets at the right-hand side of the commutator and which come into use for the 110 purpose of signaling "down" service are arranged in circuits, as follows, viz: From the "down" push-button of the sixth floor a wire a leads to the releasing-magnet T at the right-hand side of the shaft H, and this magnet T 115 is connected by a wire q with the wire x³, that leads to the rotary transformer V. Hence it will be seen that if a party on the sixth floor desires "down" service and depresses the "down" push-button current will pass from the rotary transformer V, by wire v, through switch W, (at such time closed,) to wire x', to the "down" push-button on the sixth floor, thence by wire a to the magnet T, thence by wire q and wire x³ back to transformer V. 120 The magnet T will thus be energized and will cause the armature r of the magnet R to be released, thus permitting the contact-rod s to drop into the mercury-pot S and close the circuit at such point. The "down" push-buttons on the fifth, fourth, third, and second 125 floors are connected by wires a', a², a³, and a⁴, respectively, with the releasing-magnets T', T², T³, and T' at the right-hand end of the com-

mutator, and it will thus be seen that by the operation of either of the "down" push-buttons the corresponding releasing-magnet will be energized in order to close the circuit at the 5 mercury-pot adjacent such magnet.

In order to cause the signal-lantern E or F to burn as the car moving in the desired direction approaches the floor at which the signal is given, electric lamps within these lanterns are arranged in circuits next to be described.

With the feed-wire f that leads from the dynamo Y connects a branch feed-wire f^5 , and this branch feed-wire f^5 is tapped by a series 15 of inlet-wires f^6 , that lead to the corresponding lanterns upon the several floors of the building.

The "down" lantern E on the top floor is connected by wire z with contact-plate 36 on 20 the left-hand side of the commutator screw-shaft, (see Figs. 1 and 3,) it being understood that Fig. 3 is an inverted plan view, thus causing the contact-plates to be shown upon the opposite side of the screw-shaft. The 25 plate 36 is arranged in the path of travel of the contact-brushes i' and j' on the supplemental cross-arms H^7 and H^8 during the final part of the "up" movement of these arms. The "down" lanterns on the several floors below 30 the top floor are connected, respectively, by wires z^1 , z^2 , z^3 , z^4 , and z^5 with the contact-plates 30, 29, 28, 27, and 26. (See Fig. 1.) The lighting of the "down" lantern on the top floor will occur automatically as the elevator-car approaches such floor, at which time 35 the contact-brush i' will bear against the contact-plate 36 and the contact-brush i will bear against the plate 45. Current will then pass from the dynamo Y, by wire f and branch wires f^5 and f^6 to the "up" lantern F on the bottom floor, thence by wire z^6 to contact-plate 46, thence to contact-brush j , thence by cross-wire i^{10} to contact-brush j' to contact-plate 25, thence by wire z^5 to plate R^6 , to wire f^2 , to wire f^3 , and back to dynamo Y. The "up" lantern upon the first floor will thus be caused to automatically burn as the car approaches the first floor and while it rests at such point. When 40 the "up" push-button on the second floor is operated, current will be caused to pass through "up" lantern on such floor, as follows, viz.: from dynamo Y by wire f^5 to "up" lantern E on the second floor, thence by wire z^7 to contact-plate 40, thence to contact point or brush z , (which at the end of the 45 down movement of the elevator-car has been shifted upon plate 46 to plate 40,) thence from said contact point or brush z by wire j^{10} to contact point or brush j' , thence to contact-plate 31 by wire leading from said contact-plate 31 to the mercury-pot S^4 , thence through the contact-rod of said mercury-pot to the contact-plate R^6 , to wire f^2 , to wire f^3 , and back to dynamo Y. The light will continue within the 50 "up" lantern of the second floor until during the upward movement of the elevator-car and corresponding operation of the commutator mechanism the contact brush or point j passes from off the contact-plate 40.

Having thus shown how the signal-lamp within the elevator-car and the signal-lanterns upon the several floors of the building will be caused to burn by the operation of the push-buttons on such floors, it remains to be shown how the parts of the commutator will be restored to normal position after the desired signal has been given. By reference

the time that the elevator-car passes the sixth floor in its downward movement the contact-point i' will pass off the contact-plate 30, and 70 the circuit at such point will be broken and the light within the lantern will be extinguished. In the same manner it will be readily seen that the "down" lantern on each floor will be caused to burn when the push-button upon such floor is operated.

The "up" lantern F on the bottom floor is connected by a wire z^6 with the contact-plate 46 at the right-hand side of the commutator-shaft, as seen in Fig. 1, (shown at the left-hand side in inverted plan view Fig. 3,) and the "up" lantern F on the second floor is connected by a wire z^7 with contact-plate 40. In like manner the "up" lanterns between the second and top floors are connected, respectively, with the contact-plates 41, 42, 43, and 44. From the foregoing description it will be seen that the lighting of the "up" lantern on the bottom floor is effected automatically as the car approaches such floor, since 85 at such time the corresponding travel of the contact-brushes will cause the contact-brush j to bear against the contact-plate 46, while the contact-brush j' will bear against the contact-plate 25. Current will then pass from the 90 dynamo by wire f and branch wires f^5 and f^6 to the "up" lantern F on the bottom floor, thence by wire z^6 to contact-plate 46, thence to contact-brush j , thence by cross-wire i^{10} to contact-brush j' to contact-plate 25, thence by wire z^5 to plate R^6 , to wire f^2 , to wire f^3 , and back to dynamo Y. The "up" lantern upon the first floor will thus be caused to automatically burn as the car approaches the first floor and while it rests at such point. When 95 the "up" push-button on the second floor is operated, current will be caused to pass through "up" lantern on such floor, as follows, viz.: from dynamo Y by wire f^5 to "up" lantern E on the second floor, thence by wire z^7 to contact-plate 40, thence to contact point or brush z , (which at the end of the 100 down movement of the elevator-car has been shifted upon plate 46 to plate 40,) thence from said contact point or brush z by wire j^{10} to contact point or brush j' , thence to contact-plate 31 by wire leading from said contact-plate 31 to the mercury-pot S^4 , thence through the contact-rod of said mercury-pot to the contact-plate R^6 , to wire f^2 , to wire f^3 , and back to dynamo Y. The light will continue within the 105 "up" lantern of the second floor until during the upward movement of the elevator-car and corresponding operation of the commutator mechanism the contact brush or point j passes from off the contact-plate 40.

Having thus shown how the signal-lamp within the elevator-car and the signal-lanterns upon the several floors of the building will be caused to burn by the operation of the push-buttons on such floors, it remains to be shown how the parts of the commutator will be restored to normal position after the desired signal has been given. By reference

to Fig. 4 of the drawings it will be readily understood that the breaking of the circuits at the mercury-pots will be effected by the energization of the restoring-magnets R R', &c., and this is accomplished as follows, viz: Let it be assumed, for example, that the car is at the second floor and that a corresponding position of the contact points or brushes of the commutator mechanism exists, and let it be assumed also that an intending passenger upon the second floor has operated the "up" push-button, thereby causing the signal-lamp within the car and the "up" lantern upon the floor to burn. When the passenger has entered the car and it begins its upward movement, the contact point or brush K² at the left-hand side of the commutator-shaft II will pass onto the contact-plate 11, and at such time (see Fig. 4) the contact-point K² will be in engagement with the contact-plate m³. (See Fig. 2.) Current will then pass from restoring-magnet R⁴ at the left-hand side of the commutator-shaft by wire 80 to contact-plate 11, thence by contact point or brush K⁴, thence to wire k¹⁰, and by a branch from this wire to a binding-post on the sleeve k⁷ at the opposite side of the commutator-shaft, thence to contact point or brush K², to contact-plate m³, (see Fig. 1,) and thence by wire S1 to the normally-closed transfer-button C within the elevator-car, thence by wire S2 to the rotary transformer V, thence by wire z³ and branch wire S3 to the restoring-magnet R⁴. Current being thus caused to pass through the restoring-magnet R⁴ at the left-hand side of the commutator-shaft, this magnet will be energized and will attract its armature r', and will thus lift the contact-rod s from the corresponding mercury-pot S⁴, and will open the electric-lighting circuit at such point. Hence it will be seen that the circuits of the electric lamp within the car and of the signal-lantern on the second floor will be restored to normal condition. If it be assumed that an intending passenger has operated the "down" button on the sixth floor, for example, and has caused the signal-lamp within the car and the signal-lantern to be lighted, the extinguishing of these signals will be accomplished in the following manner, it being assumed that a car having started downward from the top floor has reached the sixth floor and taken on the passenger: After the car passes from the sixth floor the contact brush or point K' at the right-hand side of the commutator-shaft will bear against the contact-plate 12, and current will then be caused to pass through the restoring-magnet R at the right-hand side of the commutator-shaft in the following manner: From the magnet R current will pass by wire 84 to contact-plate 12, (see Fig. 1,) then to contact-brush K', (which on the down movement of the car is in operation,) thence by wire k¹² to the binding-post of the sleeve k⁷, thence to contact point or brush K³, thence to contact-bar m³, thence by wire S1 to the

transfer-button C within the car, thence by wire S2 to rotary transformer V, thence by wire z³ and branch wire S3 to restoring-magnet R. The magnet being thus energized, the contact-rod will be lifted from the corresponding mercury-pot S, and the circuits of the lamp and signal-lantern within the car will be restored to normal condition. 75

As it often happens that a car is crowded and cannot, therefore, admit an additional passenger who may have given a signal, it is desirable that the signal should be caused to appear in the next car approaching in the desired direction. It has just been seen that in order to extinguish the signal lamps and lanterns the current that energizes the restoring-magnets R R', &c., must pass through the transfer push-button C, which is normally closed. It will be readily understood, therefore, that if, as while the car is passing the floor at which the signal is given, the operator should depress the transfer-button C and break the circuit at such point then no current could pass through the corresponding restoring-magnet, as the contact-brush passed onto the contact-plate corresponding to such floor. Hence the circuits will be left in condition to operate the signal lamp and lantern 95 of the next car approaching the floor in the desired direction in order that it may stop to take on the passenger.

In the accompanying drawings two elevator-cars are shown in juxtaposition and each 100 car is shown as provided with its commutator mechanism. The commutator mechanism for all the elevator-cars will be substantially identical, except that for convenience the releasing and restoring magnets and the mercury-pots are arranged upon one of the commutator-frames. Obviously, however, these parts might be placed in any convenient location. It is not deemed necessary to describe in detail the commutator mechanism illustrated at 105 the right-hand side of Fig. 1 of the drawings, which mechanism is also illustrated in Figs. 5 and 6 of the drawings. It will be seen by reference to Fig. 1 that this commutator mechanism is connected by suitable cross-wires 110 with the corresponding wires of the commutator hereinbefore fully described, and any one familiar with this class of mechanism will readily understand how it is that when the local circuit is established through any push-button a corresponding operation of the commutator mechanism of the various elevators 115 will occur. Thus by reference to Fig. 1 it will be seen that the wire f that leads from the dynamo Y is connected with the signal-lanterns shown at the right-hand side of the drawing, while the wire b that leads to the electric lamp within the car A has a branch b⁸ that leads to the electric lamp within the car A', and from this lamp a wire b¹⁰ leads to 120 the contact-plate m³, as in the construction hereinbefore described. It will be observed also that a series of cross-wires 90 connect the contact-plates 12, 13, 14, 15, and 16 at the

right-hand side of the commutator-shafts of both commutators, and in like manner a series of wires 91 connect the restoring contact-plates 7, 8, 9, 10, and 11 at the left-hand side 5 of both commutators. It will therefore be understood that when a signal has been given on any floor of the building the first car reaching such floor will cause the corresponding movement of its commutator mechanism and 10 will restore the circuits at the corresponding mercury-pot on the frame of the master-commutator to normal condition.

It will be understood, of course, that the precise details of construction above set out may 15 be varied without departing from the spirit of the invention. Thus, for example, the contact-plates of the commutators may be so arranged as to give the signals at any desired distance in advance at which the cars are to 20 be stopped, and other changes may be made within the scope of the invention.

Having thus described our invention, what we claim as new, and desire to secure by Letters Patent, is—

25 1. An electric signaling apparatus for elevators comprising push-button or like mechanism located at the floors of the building, visual signals such as lanterns also located at the floors of the building and a commutator mechanism for controlling the passage of current through said signals, said commutator 30 mechanism comprising a screw-shaft, a carrier-nut mounted upon said shaft and arranged to move in unison with the elevator-car, contact-brushes carried by said carrier-nut and contact-plates with which said 35 brushes engage, said contact-plates being arranged in correspondence with the floors of the building and being in circuit with the visual signals, whereby as the brushes pass over 40 said plates the passage of current through the individual circuits of the visual signals is determined.

45 2. An electric signaling apparatus for elevators comprising a signal within the elevator-car, lanterns or visual signals located along the elevator-shaft at the different floors, push-button or like mechanism whereby passage of current through said signals is determined 50 and a commutator operated by the elevator mechanism, said commutator being provided with plural series of contact-plates corresponding to the floors of the building, certain 55 of said contact-plates being in circuit with the corresponding signal within the car and others of said contact-plates being in circuit with the corresponding signals upon the elevator-floors, and comprising also contact-brushes and means for moving said brushes 60 across said contact-plates in unison with the movement of the elevator-car, certain of said brushes serving to control the circuit wherein the signal within the car is placed and others of said contact-brushes serving to control the 65 circuits of the signals upon the floors of the building.

3. A commutator for elevator-signaling apparatus comprising a screw-shaft, a carrier-nut engaging said shaft and provided with a brush-supporting arm pivotally sustained 70 with respect to said carrier-nut, brushes at opposite ends of said brush-supporting arm, two sets of contact-plates at opposite sides of said screw-shaft, the turning of the carrier-nut serving to effect a lateral shift of the 75 brushes from one set of contact-plates to another as the travel of the nut is reversed.

4. A commutator for elevator-signaling apparatus comprising a screw-shaft, a carrier-nut mounted thereon and provided with a 80 cross-arm extending in opposite directions from the shaft, a plurality of contact brushes or points at the ends of said arm, a plurality of insulated contact-plates arranged parallel with the screw-shaft at the opposite sides 85 thereof, with which contact-plates said brushes will engage, a supplemental cross-arm sustained by said carrier-nut and provided at its opposite ends with contact-brushes and supplemental contact-plates at 90 opposite sides of said screw-shaft with which the brushes of said supplemental arm will engage, the oscillation of the carrier-nut serving to shift both the cross-arm and the supplemental arm.

95 5. A commutator for elevator-signaling apparatus comprising a screw-shaft, a nut engaging said shaft and carrying an oscillating brush-supporting arm, contact-plates arranged along the path of travel of said brush-supporting arm and a friction-block between said carrier-nut and said shaft.

6. A commutator for elevator-signaling apparatus comprising a screw-shaft, a nut engaging said shaft and carrying an oscillating 105 brush-supporting arm, contact-plates arranged along the path of travel of said brush-supporting arm and a spring-actuated friction-block between said carrier-nut and said shaft.

110 7. A commutator for elevator-signaling apparatus comprising a screw-shaft, a nut engaging said shaft and carrying an oscillating brush-supporting arm, contact-plates arranged along the path of travel of said brush-supporting arm, a spring-actuated friction-block between said carrier-nut and said shaft and a screw for adjusting the tension or bearing 115 of the spring upon said block.

8. A commutator for elevator-signaling apparatus comprising a screw-shaft, a carrier-nut mounted upon said shaft and movable lengthwise thereof and one or more adjustable stop-nuts for determining the end of travel of said carrier-nut.

120 9. A commutator for elevator-signaling apparatus comprising a screw-shaft, a carrier-nut mounted upon said shaft and serving to support the contact-brushes of the commutator, bearing-plates at the end of the travel of 130 said carrier-nut and at the opposite sides of the nut, said bearing heads or parts engaging

parts carried by said nut and serving to take the strain thrown upon said nut by the turning of the shaft.

10. A commutator for elevator-signaling apparatus comprising a rotating screw-shaft, a carrier-nut mounted thereon and carrying the contact-brushes of the commutator and provided at its sides with flanges or extensions and bearing heads or parts located at the end 10 of travel of the carrier-nut and serving to engage said flanges or extensions.

11. A commutator for elevator-signaling apparatus comprising a rotating screw-shaft, a carrier-nut mounted thereon and carrying the 15 contact-brushes of the commutator and provided at its sides with flanges or extensions and bearing-heads located at the end of travel of the carrier-nut and serving to engage said flanges or extensions, said bearing-heads 20 having inclined ends adapted to engage the flanges or extensions at the sides of the carrier-nut.

12. A commutator for elevator-signaling apparatus comprising a screw-shaft, a carrier-nut mounted upon said shaft and supporting 25 the contact-brushes of the commutator, an arm extending from said carrier-nut and a guard-bar along the opposite sides of which said arm will travel as the carrier-nut moves 30 in opposite directions, said guard serving to prevent the tilting movement of the carrier-nut at points between the ends of its travel.

13. A commutator for elevator-signaling apparatus comprising a screw-shaft, a carrier-nut mounted upon said shaft, a cross-arm supported by said carrier-nut and provided with 35 a plurality of contact-brushes at its opposite ends, an arm depending from said carrier-nut, a supplemental cross-arm sustained by said 40 depending arm and provided with contact-brushes at its opposite ends and individual contact-plates arranged in the path of travel of the brushes carried by the cross-arm and the supplemental arm.

45 14. A commutator for elevator-signaling apparatus comprising a screw-shaft, a carrier-nut mounted upon said shaft and supporting the contact-brushes of the commutator, an arm extending from said carrier-nut and a 50 guard-bar along the opposite sides of which said arm will travel as the carrier-nut moves in opposite directions, said bar being shorter than the travel of said arm whereby when the carrier-nut reaches the extremes of its travel 55 it will pass from engagement with said bar.

15. A commutator for elevator-signaling apparatus comprising a screw-shaft, a carrier-nut engaging said shaft, a cross-arm extend-

ing laterally from each side of said carrier-nut, a contact-bar extending along the path 60 of travel of said nut at each side thereof, individual contact-plates also arranged along the path of travel of said nut, and plural contact-brushes carried at each end of said cross-arm, the contact-brushes arranged opposite 65 said contact-bars at both sides of said nut being in constant engagement with said bars during the travel of the nut in opposite directions.

16. A commutator for elevator-signaling apparatus comprising a screw-shaft, a carrier-nut engaging said shaft, a cross-arm extending laterally from each side of said carrier-nut, a contact-bar extending along the path 70 of travel of said nut at each side thereof, individual contact-plates also arranged along the path of travel of said nut, and plural contact-brushes carried at each end of said 75 cross-arm, the contact-brushes arranged opposite said contact-bars at both sides of said 80 nut being provided with springs that hold them in constant engagement with said bars during the travel of the nut in opposite directions.

17. In electric signaling apparatus for elevators, the combination of visual signals for the several elevator-cars, individual commutators for controlling the passage of current through said visual signals, a restoring mechanism whereby said visual signals are brought 85 to inactive condition, electric circuits leading from said restoring mechanism to the elevator-cars and a circuit-controlling mechanism within each car whereby the signal-restoring mechanism can be controlled to permit the signal to stand for the next succeeding car.

18. In an electric signaling apparatus for elevators, the combination of visual signals for several elevators, individual commutators 100 for controlling the passage of current through said signals, said commutators comprising means for restoring said signals to inactive condition and a circuit-controlling mechanism such as a transfer-button within each car, 105 said transfer-buttons being connected with the restoring mechanism of said commutators in such manner that by the actuation of said buttons the operation of the restoring mechanism of the corresponding commutator can 110 be prevented.
